WILLIAM D. WOOD, OF SAN FRANCISCO, CALIFORNIA.

SWITCHING DEVICE.

Application filed May 31, 1927. Serial No. 195,257.

This invention relates to a switching device and especially to a multiple switch structure for signalling devices, telephone work, organ stop and coupler action controls, etc.

Heretofore switches of the character described have been constructed either with a flexible contact at both sides of a movable circuit closer or by a series of stationary contacts 10 having flexible contacts movable to engage the same. The disadvantage of the former is that double the number of wires or cables are required, while the disadvantage of the latter is that considerable 15 pressure and consequently powerful magnets or pneumatics are required to hold the series of contacts in the on position.

It might be stated that a low voltage current is employed and the power available 20 for operation is comparatively small and it is accordingly essential that the switch mechanism be capable of operation with a minimum of power.

The object of the present invention is to 25 generally improve and simplify the construction and operation of switches of the character described and more particularly to provide a multiple switch structure in which a plurality of aligned superposed 30 rigid and flexible contacts are employed between which a plurality of combination oscillating and reciprocating circuit closing bars are operated in unison in such a manner that a minimum of pressure and power will 35 be required.

The switch structure is shown by way of illustration in the accompanying drawings in which:

Fig. 1 is a plan view of a multiple switch. 40 Figs. 2 and 3 are vertical cross-sections of the switch said views showing the on and off position assumed by the circuit closing bars.

Fig. 4 is a perspective view of one of the 45 circuit closing bars, the rocker in which it is supported and guided, and said view also showing the rigid and flexible contacts with which the circuit closing bar cooperates.

The switch illustrated in the present instance is particularly intended for pipe 50 organ stop and coupler action control and as switches of this character carry a comparatively low voltage current, wood or a similar material is usually employed, as such material has proven a sufficient insulator. It 55 will accordingly be noted that the switch

consists of a main base plate A, referring to Figs. 1, 3 and 4, which is constructed of wood or a similar material. Extending cross-wise of the base and resting on the 60 upper surface thereof are a plurality of interspaced rigid rods such as indicated at 2.

The forward ends of the rods are secured to the base by means of a clamping bar 3, which extends from end to end thereof. The opposite ends of the rods are bent at right angles, as indicated at 4, and the rear edge of the base A is perforated to permit the right angular extensions to extend therethrough. Disposed at opposite ends of the base is a 70

pair of supporting blocks 5-5, which serve two functions: first, that of a bearing for a rocker arm, generally indicated at B and secondly, that of a support for a secondary base plate, generally indicated at C. This

base plate is also constructed of wood and it forms a support for a plurality of flexible spring actuated wire contact rods, generally indicated at 6. These contact rods are mounted in alignment with the rigid rods 80

2. They are secured to the secondary base C by means of a perforated clamping bar 7 which extends from end to end of the plate C. The rear ends of the flexible contact wires or rod 6 are turned at right angles, as indicated at 8, and they extend upwardly through the perforated clamping plate. Each rod is provided with a coil or spring 85

loop 9 and the forward end of each rod passes through a slotted plate 10 which forms guides therefor and maintains the forward ends of the wires or rods 6 in alignment with the rods 2. A strip of felt 11, or like material, is positioned rearwardly of the slotted guiding plate 10 and forms a support 90

for the forward ends of the wire rods 6, the tension produced by the loops or coils 9 being sufficient to maintain such contact. 95

The rocker arm B extends substantially from end to end of the base plate A and is provided with pivot rods 12 at its opposite ends, which are journaled in the blocks 5. The rocker arm is slotted vertically to support and guide a plurality of circuit closing 100

bars 14. One of the bars is best illustrated in Fig. 4. By referring to this figure it will be noted that the lower end of each bar is rounded, as at 15, so as to ride upon and to be guided by the rigid rods 2. The upper ends are similarly rounded, as indicated at 110

16, and as the upper ends cooperate with the flexible wire spring rods 6, a guide will also

be formed at this point. There is one bar 14 for each set of aligned rods, 2 and 6. All of the bars 14 are freely slideable in the rocker arm B and when a rocking movement is imparted thereto, as by means of a lever extension such as shown at 17, the circuit closing bars will swing from the incline or off position shown in Fig. 2 to the vertical or on position shown in Fig. 3. In other words, an oscillating or rocking movement and a reciprocating movement is imparted to the circuit closing bars 14 in unison when the circuits are to be closed. This is important, as a movement of this character first of all produces a wiping action with relation to the rods 2 and 6, thereby maintaining them clean and polished for proper contact. Secondly, the amount of friction imposed is comparatively small and as this is the case the rocker arm B may be swung about its pivotal support with a minimum of effort and power, while closing a number of individual circuits. Comparatively little pressure is exerted by the spring contacts or wire rods 6 and danger of warping or misalignment is avoided. The entire structure is exceedingly simple, rigid and compact, and the terminal ends indicated at 4 and 8 are so arranged and exposed that the circuit wires indicated at 18 and 19 may be readily connected or applied.

It is customary, especially in stop action of organs, to use the same stop at different pitches requiring five or more multiple switch bars to accomplish this.

It should be understood from the foregoing that one set of wires may be used to carry the current to the magnets of a certain stop with one cable therefrom, then by using five sets of multiple switches, such as here illustrated, five cables are required to furnish the current from the key or relay contact to the switch but only one cable will be required to carry the current to the pipe magnets.

While the switch has been particularly described in connection with organ construction, it is obvious that it may be employed in a great number of instances, for instance, in telephone switch work, signaling devices, etc.

I also wish it understood that while certain features have been more or less specifically described and illustrated, various changes may be resorted to within the scope of the appended claims; similarly, that the materials and finish of the several parts employed may be such as the manufacturer may dictate or varying conditions or uses may demand.

What I claim and desire to secure by Letters Patent is:

1. In a switch of the character described a base plate, a plurality of interspaced rigid contact members supported thereby; a plu-

rality of flexible contacts, one for each rigid contact; a rocker member disposed between the contacts and a plurality of circuit closing bars reciprocally mounted in the rocker member and guided thereby, said circuit closing bars being in constant contact with the rigid contact bars and movable to and away from the flexible contacts during oscillating movement of the rocker member. 70

2. In a switch of the character described 75 a base plate, a plurality of interspaced rigid contact members supported thereby; a plurality of flexible contacts, one for each rigid contact; a rocker member disposed between the contacts; a plurality of circuit closing bars reciprocally mounted in the rocker member and guided thereby, said circuit closing bars being in constant contact with the rigid contact bars and movable to and away from the flexible contacts during oscillating movement of the rocker member, 80 and means whereby an oscillating movement is transmitted to the rocker member. 85

3. In a switch of the character described 90 a base plate, a plurality of interspaced rods extending cross-wise of the base plate; means whereby opposite ends of the rods are secured; a secondary base plate disposed above the first named base plate; a plurality of interspaced flexible wire rods supported 95 by said secondary base plate, said flexible wire rods being placed in alignment with the first named rods; means securing one end of the flexible wire rods with relation to the secondary base; means whereby the opposite ends of the flexible wire rods are guided; 100

a rocker arm pivotally mounted between the first and last named wire rods and extending substantially from end to end of the base plate; means for imparting pivotal 105 movement to said rocker arm, said rocker arm having a plurality of slots formed therein, one slot for each pair of aligned wire rods, and a circuit closing bar reciprocally mounted in each slot and guided thereby, 110 said circuit closing bars being in constant contact with the first named wire rods and being movable to and away from the flexible wire rods during pivotal movement of the 115 rocker member.

4. In a switch of the character described 120 a base plate, a plurality of interspaced rods extending cross-wise of the base plate; means whereby opposite ends of the rods are secured; a secondary base plate disposed above the first named base plate; a plurality of interspaced flexible wire rods supported 125 by said secondary base plate, said flexible wire rods being placed in alignment with the first named rods; means securing one end of the flexible wire rods with relation to the secondary base; means whereby the opposite ends of the flexible wire rods are guided; a rocker arm pivotally mounted between the first and last named wire rods 130

and extending substantially from end to end of the base plate; means for imparting pivotal movement to said rocker arm, said rocker arm having a plurality of slots formed 5 therein, one slot for each pair of aligned wire rods; a circuit closing bar reciprocally mounted in each slot and guided thereby, said circuit closing bars being in constant contact with the first named wire rods and being movable to and away from the flexible 10 wire rods during pivotal movement of the rocker member; said circuit closing bars being rounded at their opposite ends so as to be guided with relation to the first and second named wire rods.
